[57] CLAIM

The ornamental design for a jewelry display case, substantially as shown.

DESCRIPTION

FIG. 1 is a perspective view of my jewelry display case showing my new design in the closed position;

FIG. 2 is a perspective view thereof, with one panel in the open position;

FIG. 3 is a perspective view thereof, with the drawer in the open position;

FIG. 4 is a side elevational view, taken from the right of FIG. 1, with both panels in the open position;

FIG. 5 is a front elevational view thereof;

FIG. 6 is a rear elevational view thereof; and

FIG. 7 is a top plan view thereof.
